UNITED STATES PATENT OFFICE.

GEORGE H. McMULLEN, OF MALVERN, PENNSYLVANIA.

FENCE.

1,055,775.

Specification of Letters Patent. Patented Mar. 11, 1913.

Application filed June 28, 1912. Serial No. 705,910.

To all whom it may concern:

Be it known that I, GEORGE H. McMULLEN, a citizen of the United States, residing at Malvern, in the county of Chester and State 5 of Pennsylvania, have invented certain Improvements in Fences, of which the following is a specification.

My invention relates more particularly to a post having improved means for securing thereto the wires of which the fence is composed.

The primary object of my improvements is to provide a simple and inexpensive post that can be driven, has a firm engagement 15 with the earth, and is braced against bending strains, in combination with simple, inexpensive and convenient means for fixing wires thereto in a secure and efficient manner.

The nature and characteristic features of 20 my improvements will more fully appear from the following description and the accompanying drawings in illustration thereof.

In the drawings, Figure 1 is a side elevation of a fence embodying my improvements; Fig. 2 is an elevation of a section of a post in combination with a wire and means 25 for securing it to the post; Fig. 3 is a vertical sectional view of the construction shown in Fig. 2; and Fig. 4 is a transverse 30 sectional view of the post with means for fastening the wire thereto shown in plan.

As illustrated in the drawings, the posts A are made from angle iron cut to proper length and having the longitudinal edges of 35 their legs a turned inwardly to form flanges a¹ extending substantially at right angles to the respective legs preferably from the tops of the posts approximately to the ground line.

10 The fence wires b are placed against the flanges a¹ of the posts where they are secured by fasteners C. These fasteners are suitably formed from approximately rectangular plates adapted to approximately 15 fit within the members a and a¹ and have their forward corners turned inwardly to form hooks for engaging the wires b, lateral corners c¹ which bear against the flanges a¹, and rear corners c² between which and the 20 junction between the legs of the posts nails D are driven so as to tilt the fasteners and press the corners c¹ against the flanges a¹,

which act as fulcrums therefor, and draw the hooks c against the wires b so that the latter are firmly pressed against the flanges a¹. These fasteners permit the wires to be fastened at any desired position with equal facility, securely hold them in the position in which they are placed, the attachment is very readily made, a desired dissociation 60 can be effected without difficulty, and the parts, as well as the operations, are simple, inexpensive, and efficient.

The post is inexpensive, being readily formed from common angle iron stock, and 65 the flanges not only considerably increase the stiffness of the post in its original form but also provide improved bearing means for preventing the lateral movement of the post.

Having described my invention, I claim:

1. A fence comprising a post having flanges, a wire, a member having a part engaging said wire and bearings engaging said flanges, and a device movable longitudinally 75 of said post for tilting said member and causing it to press said wire against said post.

2. A fence comprising an angle iron section having edges of its legs turned inwardly, a wire engaging said edges, a member having a hook engaging said wire and bearings engaging said edges, and means between said angle and member whereby said hook is caused to press said wire against said 80 edges.

3. A fence comprising an angle iron section having inturned flanges on the legs thereof, a wire, a fastener of approximately quadrilateral form engaged within said section so that corners thereof bear against 90 said flanges, said fastener having a hook thereon engaging said wire, and a nail driven between said fastener and angle section so as to force said corners against said flanges 95 and said hook against said wire.

4. A fence comprising a post having inturned flanges, a wire, a fastener having corners engaging said flanges and a corner bent so as to engage said wire, and a nail 100 driven between said post and fastener so as to tilt the same and draw said wire against said post.

5. A fence comprising a post having in-

turned flanges, a member having bearings fulcrumed on said flanges within said post and a hook, a wire engaged by said member and a device driven between said post and member, whereby said member is turned on said bearings and caused to press said wire against said post.

In witness whereof I have hereunto set my name this 25th day of June, 1912, in the presence of the subscribing witnesses.

GEORGE H. McMULLEN.
